(57) **CLAIM**

The ornamental design for a child carrier, as shown and described.

DESCRIPTION

FIG. 1 is a perspective view of the child carrier;

FIG. 2 is a front elevation view thereof;

FIG. 3 is a right elevation view thereof;

FIG. 4 is a rear elevation view thereof;

FIG. 5 is a left elevation view thereof;

FIG. 6 is a top plan view thereof;

FIG. 7 is a perspective view thereof, wherein a neck support is shown in a second position of use;

FIG. 8 is a perspective view thereof, wherein side seat flaps are shown in a second position of use; and,

FIG. 9 is a rear elevation view of FIG. 8.

The structural features depicted by broken line-work have been provided for the purpose of illustrating portions of the child carrier that form no part of the claimed design.
